UNITED STATES PATENT OFFICE.

JOHN E. GLIDDEN, OF BEVERLY, MASSACHUSETTS, BY SADIE E. GLIDDEN, GUARDIAN;
SAID SADIE E. GLIDDEN, ADMINISTRATRIX OF SAID JOHN E. GLIDDEN, DECEASED,
ASSIGNOR TO UNITED SHOE MACHINERY COMPANY, OF PATERSON, NEW JERSEY,
A CORPORATION OF NEW JERSEY.

COMPRESSING-MACHINE.

1,147,160.

Specification of Letters Patent. Patented July 20, 1915.

Application filed July 13, 1910. Serial No. 571,774.

To all whom it may concern:

Be it known that JOHN E. GLIDDEN, of Beverly, in the county of Essex and State of Massachusetts, insane, invented certain 5 Improvements in Compressing-Machines, of which the following description, in connection with the accompanying drawings, is a specification, like reference characters on the drawings indicating like parts in the several 10 figures.

This invention relates to heel compressing machines, and more particularly to molds for use in such machines.

The present embodiment of the invention 15 is particularly adapted for use in a machine of the type disclosed in United States Letters Patent No. 776,787, granted December 6, 1904, but it should be understood that reference is made to said patent for purposes 20 of illustration only, and that the invention is not limited in its application to use in this particular machine.

It is often desirable to mold a heel with the tread face thereof on top and the heel seat on the underside, especially when molding that type of heel having a tread face of larger area than the heel seat. This can be done by the substitution of a flat plate for the heel seat die, and a suitably formed heel seat die for the top lift plate in the machine shown in the patent above referred to, but the molded blank cannot then be successfully ejected from the mold, since the surface of the heel seat die is inclined and consequently 30 35 can not be brought flush with the top of the mold, which is horizontal.

An object of the present invention accordingly consists in the production of a heel seat die which can be automatically positioned so that the compressed heel may be ejected from the mold with ease and certainty.

In practice, the invention is preferably embodied in a die having an inclined convex 45 face suitably formed for molding a heel seat upon a heel, the die being yieldingly mounted for pivotal movement within a mold, and forming the bottom thereof. Suitable means, such as a spring, tends to move one end of the 50 die into such a position that the seat forming surface of the die is, in general, approximately either parallel to or flush with the top of the mold. The die may be mounted

upon a support vertically movable within the mold so that the die may, at the proper 55 point in the cycle of operation of the machine, be moved into such a position that its surface is substantially flush with the top of the mold, when the compressed heel resting upon the surface of the die may be easily 60 pushed off by the feeding mechanism of the machine as a new blank is being brought into compressing position thereby. By reason of the pivotal mounting of the heel seat die it is possible to elevate its rear end until the 65 upper surface of the die at that point is on a level with the top of the mold and yet not allow the breast end of the die to project above the top of the mold into the path of the clamping arms of the blank feeding 70 device.

Since the die is yieldingly mounted it can, under the molding pressure, assume the proper position to form the inclined heel seat correctly upon the blank being operated 75 upon.

The details of a preferred form of the invention will be set forth in the following description taken in connection with the accompanying drawings in which,—

Figure 1 is a central sectional view of the heel seat die and the mold in which it is mounted; and Fig. 2 is a perspective view of the heel seat die and its mounting plate and spindle.

In the drawings, numeral 1 indicates a reciprocating cross head upon the upper surface of which rest side dies 2 and a breast die 3. The said side and breast dies are mounted to slide laterally toward and from 90 each other upon the upper surface of the cross head and thus form a mold which is capable of contraction and expansion.

Within a countersunk bore in the cross head 1 a bushing 4 is supported. The bushing is centrally bored to receive the spindle 5, to which the supporting plate 6 is rigidly attached by means of the pin 7. Upon the supporting plate 6 is mounted the heel seat die 8 by means of the pivot pin 9 which 100 passes through a lug 10 projecting upwardly from the plate 6 into a recess in the breast end of the die 8. A spring 11 interposed between the plate 6 and the die 8 normally tends to urge the rear portion of the said die 105 upwardly into the position shown in Fig. 1.

The spring 11 surrounds a screw 12, the point of which enters the die 8 and the head of which engages a shoulder 13 in the hole 14, which extends through the plate 6 and within which the screw head may move vertically. The screw head and the shoulder 13 thus constitute means for limiting the upward movement of the rear end of the heel seat die 8.

The heel seat die 8 may be provided with the usual convex projection 15 for forming a lip in the breast end of the heel seat. 16 indicates a stationary follower or compressing member having a flat under surface for forming a tread face upon a heel blank. The follower is so located and proportioned that when the mold is closed upon the heel blank to compress the blank laterally and the cross head carrying the mold is then moved upwardly toward the stationary follower, the latter will enter and be closely embraced by the side wall of the mold. One of the blank clamping arms of a heel feeding device is indicated at 17. The feeding device may be of any preferred form, preferably similar to that shown in the patent previously referred to. A pin 18 is yieldingly pressed to enter the recess 19 in the spindle 5 by the spring 20, and may be withdrawn sufficiently to allow the removal of the spindle with the supporting plate and heel seat die mounted thereon from the mold.

The dotted lines in Fig. 1 show the position into which the heel seat die 8 is moved when it is desired to eject the compressed heel from the mold. It will be readily seen that if the heel seat die were not tilted from the position in which it lies while the heel blank is being compressed, the compressed blank could not be ejected successfully from the mold by the rearwardly moving clamping arms 17 since if the die were only elevated until the upper edge of the lip forming projection 15 were flush with the top of the mold, then the rear end of the blank would still be a considerable distance within the mold and the heel could not be pushed rearwardly off the heel seat die. If the die be raised high enough to allow the rear edge of the heel to move over the top of the mold then the projection 15 would be in the path of the arms 17 and damage to the machine would result. The parts are, therefore, so designed that when the rear end of the heel seat die is elevated by the spring 11 into the position shown in Fig. 1, the edge 18 will be elevated to the same level as the upper edge of the projection 15. The die may then be moved upwardly into the position shown in dotted lines and the compressed heel may be readily removed therefrom by the arms 17.

The operation of the device is as follows:—Assuming that the cross head 1 is in its lowered position and a heel blank has been placed within the mold upon the die

8, the cross head is moved upwardly. During the first part of the upward movement of the cross head the side dies 2 and the breast die 3 are moved horizontally toward each other to compress the heel blank laterally. In the continued upward movement of the cross head and the mold carried thereon, the upper surface of the blank will engage the follower 16. The vertical pressure thus brought to bear upon the blank will first depress the rear end of the die 8 against the tension of the spring 11 until the under side of the die rests upon the supporting plate 6 and the heel seat forming upper surface thereof assumes an inclined position with relation to the surface of the follower 16. The upper surface of the die 8 is properly convexed to mold the seat surface upon the heel blank. As the mold is moved farther upward, the blank is compressed and molded between the follower 16 and the die 8. As the mold again moves downwardly, the side and breast dies are first moved outwardly, thus relieving the heel of lateral pressure. The heel seat die is then elevated into the position shown in dotted lines in Fig. 1, its rear end being elevated by the spring 11. A new heel blank is then brought by the clamp 17 into position to be deposited upon the heel seat die, the advancing ends of the arms 17 pushing the previously compressed heel off the surface of the die. The die and heel blank are then lowered into the mold and the operation just outlined is repeated.

Having fully described the invention, what is claimed as new and desired to be secured by Letters Patent of the United States is:—

1. A heel compressing machine having, in combination, a heel seat die movable from an inclined to an approximately horizontal position, and automatic means tending normally to keep the die in the latter position.

2. In a machine of the class described, the combination of an angularly movable heel seat die having a curved face, and means tending to maintain the central points of the breast and rear edges of said face in approximately the same horizontal plane.

3. In a machine of the class described, the combination of angularly yielding means for forming an inclined heel seat surface upon a heel blank, and means tending to maintain said heel seat forming means in a generally horizontal position.

4. In a heel compressing machine, side compressing members, and a heel seat die vertically movable between said side compressing members, said heel seat die being mounted between said members for movement about a pivot.

5. In a machine of the class described, the combination of side and breast dies, a heel seat die always within the mold formed by said side and breast dies, means for feeding a heel blank to said mold, and means for

holding the central portion of the edge of the heel seat molding surface from which the heel is ejected at approximately the same level as the central portion of the edge of 5 said surface to which the heel is fed, while the heel is being ejected from the mold.

6. In a compressing machine, a stationary follower, a crosshead movable toward and from said follower, means for placing a 10 blank in compressing position, and means for ejecting a compressed blank, said ejecting means comprising a member mounted for movement about a horizontal pivot and engaging the under side of the blank.

15 7. A machine for compressing shoe parts, comprising the combination of a stationary compressing member, a vertically movable crosshead between which and said stationary compressing member a blank may be compressed, and ejecting mechanism comprising a vertically movable spindle, a member pivotally connected to said spindle and a spring between said last mentioned member and said spindle.

20 8. A machine for compressing shoe parts, comprising the combination of a stationary compressing member, a crosshead movable

toward said stationary member to apply pressure to a blank placed therebetween, and ejecting mechanism comprising a spindle guided for vertical movement in said crosshead, a blank engaging plate, a pivotal connection between said plate and said spindle, and a spring tending to move said plate away from said spindle.

25 9. A machine for compressing shoe parts, comprising a stationary compressing die, a crosshead movable toward and from said die, means upon said crosshead providing a space or cavity within which a blank may be compressed, and means for ejecting the compressed blank from the machine, said ejecting means comprising a pivoted blank engaging member movable through said space or cavity and a spring tending to tilt 45 said blank engaging member about its pivot.

In testimony whereof I have signed my name to this specification in the presence of two subscribing witnesses.
